UNITED STATES PATENT OFFICE

2,241,029

HOLDING DEVICE

Robert R. Harrison, New Haven, Conn.

Application December 29, 1939, Serial No. 311,663

4 Claims. (Cl. 24—263)

This invention relates to a holding device.

An object of the invention is the construction of a holding device which will permit easy placing of the article to be supported between the jaw units and the clamping bar, by reason of the jaw units being at all times in engagement and affording a broad bearing surface to be engaged by the article.

Another object of the invention is the construction of a holding device in which the clamping bar can be forced to an unseated position, but when released will automatically slide to a clamping or locking position in cooperation with jaw units that are always in engagement.

A still further object of the invention is the construction of a novel and efficient holding device out of spring wire, whereby the action of the clamping bar is substantially automatic in conjunction with overlapping jaw units for efficiently securing an article of any description securely upon the device, whether such article be a towel, a dish cloth, a diaper, or the like.

With the foregoing and other objects in view, the invention comprises certain novel constructions, combinations, and arrangements of parts as will be hereinafter fully described, illustrated in the accompanying drawing, and more particularly pointed out in the appended claims.

In the drawing:

Figure 1 is a view in elevation of the holding device in its normal condition.

Figure 2 is a view in side elevation.

Figure 3 is a sectional view taken on line 3—3, Fig. 1, and looking in the direction of the arrows.

Figure 4 is a sectional view taken on line 4—4, Fig. 1, and looking in the direction of the arrows.

Figure 5 is a sectional view taken on line 5—5, Fig. 1.

Figure 6 is a view in front elevation of the holding device as it appears when the resilient sides are compressed, and the jaw units are in their maximum engaging position, for receiving an article between said jaw units and the clamping bar.

Figure 7 is a sectional view taken on line 7—7, Fig. 6, and looking in the direction of the arrows.

Figure 8 is a fragmentary plan view of two jaw units of another embodiment of the invention.

Figure 9 is a sectional view taken on line 9—9, Fig. 8.

Figure 10 is a fragmentary plan view of two

engaging jaw units of another embodiment of the invention.

Figure 11 is a sectional view taken on line 11—11, Fig. 10.

Referring to the drawing, and especially to Figures 1 to 7, in which I have shown the preferred embodiment of my invention, the frame 1 is formed from strong spring wire. This frame 1 comprises an eye or loop 2 with diverging arms 3; said arms 3 are provided at their outer ends with straight sides 4, and said sides 4 are provided at their outer ends with radically converging portions 5; said portions 5 terminate in inwardly-extending, permanently-engaging slideable jaw units 6. The jaw units 6 are at substantial right angles to said sides 4. The jaw units 6 provide a comparatively broad bearing surface (Fig. 5) over which to pass the article 7 (dotted lines) to be secured on the device 1; when the jaw units 6 are in their greatest engaging position (Fig. 6) at the time of inserting article 7, no possible retardment of insertion occurs, since the article has a broad bearing surface to engage, eliminating any clamping or pinching of the article between the engaging jaw units. When the jaw units are in their normal position (Fig. 1) they support the article as shown in dotted lines in a very efficient manner.

The clamping bar 8 is provided at its ends with eyes 9 that slide upon the portions 5 and sides 4.

When the operator wishes to insert an article between the jaw units and the clamping bar he forces the bar upwardly or inwardly on sides 4, thereby depressing the same, which causes the sides to appear radically converging, then when the operator releases the clamping bar, by reason of the springy action of the device, the bar automatically quickly slides towards the jaw units 6, over the radically converging portions 5 and assumes a locked position with respect to the jaw units, whereby an article between the jaw units and the bar will be securely held in position upon the holding device. The particular reason for this holding or locking of the bar in a clamped position is that the portions 5 prevent any accidental movement of the bar upon the side 4.

By reason of the straight inwardly-extending jaw units 6 at all times being in engagement, the article 7 is greatly supported upon two jaw units, irrespective as to whether the jaws are in their normal positions as shown in Figure 1 or pressed

together at their maximum engaging position, as shown in Figure 6.

The holding device 1 may be supported in any suitable manner; for instance, when it is being used in a dwelling it may be supported upon a hook 10, but if it is desired to use this device as a clothes pin, for supporting articles on a clothes line, the clothes line (not shown) can be threaded through the eye 2, and the device will operate satisfactorily.

In the embodiment shown in Figures 8 and 9, the jaw units 6a are provided with flat engaging faces 11, whereby a very snug fit is produced. These jaw units 6a are provided with flat tops 12 upon which the article supported rests during the holding operation.

In the embodiment shown in Figures 10 and 11, the jaw units 6b are provided with the flat tops 12, the same as in the embodiment shown in Figures 8 and 9. One of the jaw units 6b is provided on its inner face with a longitudinally-extending groove 13 (Fig. 11) and the other jaw unit is provided on its inner face with a longitudinally-extending rib 14; rib 14 is in the groove 13, whereby the jaw units 6b admirably slide against each other and are kept in a registering position, resulting in the tops 12 being always in the same plane.

It is to be noted that the inner ends of the jaw units in all of the embodiments are at all times between the sides 4, whether in their normal position or in a compressed position, Figs. 1 and 6, respectively.

While I have described the preferred embodiments of my invention and illustrated the same in the accompanying drawing, certain changes or alterations may appear to one skilled in the art to which this invention relates, during the extensive manufacture of the same, and I, therefore, reserve the right to make such changes or

alterations as shall fairly fall within the scope of the appended claims.

What I claim is:

1. In a holding device, the combination of a spring wire frame including substantially parallel straight sides, said straight sides terminating at their outer ends only in radically converging portions, said converging portions terminating at their outer ends in inwardly-extending parallel straight jaw units, said jaw units having their ends at all times between said sides, a clamping bar on said sides, said clamping bar provided with eyes surrounding said sides, and said eyes adapted to tightly engage said converging portions and be held securely thereby against accidental movement when said clamping bar is in its normal position contiguous to said jaw units.
- 5 2. In a holding device, the combination of a frame provided with permanently-engaging jaw units, said jaw units being flattened on their engaging side surfaces and flattened on their abutting tops throughout their length, said side surfaces only provided with interlocking means, and a clamping bar slidably mounted on said frame.
- 10 3. In a holding device, the combination of a frame provided with parallel permanently engaging jaw units, one of said jaw units provided with a groove on its inner side and the other jaw unit provided with a rib on its inner side in said groove, and a clamping bar on said frame.
- 15 4. In a holding device the combination of a frame provided with engaging jaw units, one of said jaw units provided with a longitudinally-extending groove on its inner side face and the other jaw unit provided with a longitudinally-extending rib on its inner side face, said rib seated in said groove, and a clamping bar slidably mounted on said frame.

ROBERT R. HARRISON.
